UNITED STATES PATENT OFFICE.

ARTHUR H. STURGES, OF OMAHA, NEBRASKA.

FUEL-SAVING DEVICE.

Application filed March 24, 1924. Serial No. 701,593.

To all whom it may concern:

Be it known that I, ARTHUR H. STURGES, a citizen of the United States, residing at Omaha, in the county of Douglas and State 5 of Nebraska, have invented certain new and useful Improvements in Fuel-Saving Devices, of which the following is a specification.

This invention relates to fuel saving devices, and more particularly to that class of devices which may be installed in chimneys or smoke pipes.

An object of this invention is to provide a device which will increase the efficiency 15 and economy of heating devices, particularly furnaces, stoves, and the like.

Another object of the invention is to provide a durable collapsible device which upon installation may be adjusted to meet the 20 peculiar conditions encountered with each furnace, chimney or the like.

A further object is to provide a deflector which is adjustable to direct the draft of air as desired to sweep down into the base 25 of the chimney irrespective of the size of the chimney.

The above and various other objects and advantages of this invention will in part be described in, and in part be understood from 30 the following detailed description of the present preferred embodiment, the same being illustrated in the accompanying drawings, wherein:

Figure 1 is a longitudinal section of a fuel 35 saving device constructed according to the present invention, which is installed in a chimney, a fragmentary view of the chimney and heating plant being shown in section.

Figure 2 is a front elevation of the fuel saving device.

Figure 3 is a side elevation of the same.

Figure 4 is a top plan view thereof.

Figure 5 is a longitudinal section of a 45 modified form of the device installed in a chimney, a portion of the latter being shown in section.

Figure 6 is a front elevation of the modified form, and

Figure 7 is a rear elevation of the modified form.

Referring to the drawings, and first to Figure 1, 10 designates a chimney of the usual type adapted for carrying away smoke 55 and gases from the heating plant 11 which may be of the type used for generating

steam, hot-water or the like. The gases and smoke from the heating plant 11 are carried through a smoke pipe 12 which enters a suitable opening 13 in one side of the chimney 10, and from thence the gases and smoke are carried into the atmosphere by the flue 14. It is of course understood that the chimney 10 with the flue 14 may be of any desired height and may be made of brick, 60 stone or the like and that the flue formed by the chimney may be of any desired shape. The chimney 10 has a second opening 15 which is cut through one side of the chimney at any suitable point intermediate the 70 smoke pipe 12 and the floor 16, and in which is received a metal frame 17. The frame 17 fits snugly into the opening 15 and may be cemented or otherwise secured in place. To further prevent the frame 17 75 from becoming loose, and for purposes hereinafter described, a panel 18 is provided on the outer edge of said frame which fits flush against the inner wall of the chimney 10. The upper edge of the panel 18 is provided with a plurality of lugs 19 which are in spaced apart relation to each other and serve as bearings for a rod 20.

An adjustable air deflector having side members 21 and a top member 22 is loosely 85 fitted into the frame 17, and at its outer end the top member 22 is provided with a flange 23 which substantially encircles the rod 20 intermediate its ends and intermediate the lugs 19, thus forming a hinge to permit the 90 adjustable deflector to be swung to any desired angle. The flange 23 is relatively long, and is of sufficient length to extend upwardly over the front face of the panel 18 to the rod 20 and extends downwardly 95 to support the deflector 21, 22 within the opening 15 of the chimney. A second adjustable air deflector member is provided having side members 24 and a top member 25 the inner end of the latter member terminating at a point intermediate the ends of 100 said side members 24. A third adjustable deflector member 26 has its upper edge rolled over to form a hinge engaging a rod 27 which is secured in the side members 24 105 near the inner extremity of the top wall 25. Adjacent the lower edge of the deflector member 26 and on the under side thereof is provided a plurality of lugs 28 which are in spaced apart relation to each other. A 110 rod 29 extends through suitable openings in the side members 24 and through open-

ings in the lugs 28 for securely holding the adjustable deflector member 26 in a predetermined position. Adjacent the inner ends of the side members 24 there is provided a plurality of holes 30 which are placed in spaced apart relation to each other and are arranged in an arcuate row concentric with the rod 27, and in which is received the rod 29. The rod 29 is preferably threaded at either or both ends to receive a nut 31 for securing the rod against movement. Adjacent the outer ends of the side members 24 and intermediate the upper and lower edges of said side members a series of holes 32 is provided in spaced apart relation to each other and preferably paralleled to both the upper and lower edges, said holes 32 registering with a like series of holes 33 adjacent the inner ends of the side members 21. A plurality of threaded rods 34 extend through the holes 32 and 33 for securely holding the side members 21 and 24 against movement. To further strengthen the first deflector member a plurality of braces 46 are attached to the lower edges of the side members 21 adjacent the inner and outer ends.

Intermediate the ends of the upper member 22 and on the lower side thereof is provided a lug 35 for hingedly holding an arcuate threaded rod 36 which extends outwardly and upwardly through an opening 37 on a door 38. An expanding spring 39 substantially encircling the rod 36 intermediate its ends is held at its inner end by an adjustable cup-shaped nut 40. The outer end of the spring 39 is free and is adapted to engage the inner wall of the door 38 to yieldingly support the door upon the air deflector 22 through the intermediary of the rod 36. Adjacent the outer end of the rod 36 there is provided an adjustable nut 41 for adjustably urging the door 38 against the spring 39. The upward and outward movement of the door 38 will take up the nut 41 with its rod 36 and permit the air deflectors to swing downwardly in the opening 15 of the chimney wall 10. The door 38 at its upper edge is provided with a plurality of lugs 42 which are hingedly secured to the rod 20, and at its inner edge is provided with a flange 43 which gradually increases in depth from the hinged top to the free lower end of the door 38 to abut the face of the panel 18 and maintain the door in a downwardly inclined position when shut, thus utilizing the full force of gravity on the door 38 for maintaining it closed. The flange 43 is further held in sealed position against the panel 18 by a weight 43^a which is formed at the deepest portion of the flange 43 by thickening the outer free edge of the door 38. The flange 43 at the upper edge of the door 38 has a recess at 44 to accommodate the flange 23

when the door is shut. The lower outer edge of the door 38 has a lug 45 for holding a chain 46 or the like so that the movement of the door may be controlled and operated at a distance therefrom. The fuel economizer of this invention may be installed in the chimney wall 10 at any suitable height above the floor or ground 16 by forming the opening 15 at the desired height such as shown in Figure 1 to accommodate the frame 17 and maintain the door 38 at all times above a steam pipe 16^a or any other device which may be disposed near the chimney wall 10.

The upward movement of the chain 46 raises the door 38 which simultaneously lowers the three deflecting members 22, 25 and 26 and permits the cold air to enter the opening 15. The air striking the innermost deflector 26 is deflected downward thus giving the air a circular motion as shown by the arrows 14^a which, when rising in the flue 14, wipes across the inner end of the smoke pipe 12 as shown by the arrow 14^a and checks the gases and other products of combustion in the pipe 12 and deflects the same backwardly to some extent as shown by the arrows 12^a so that the products of combustion may be entirely consumed before entering the chimney flue 14. Each deflector member may be adjusted to meet the varying conditions arising in each chimney both as to thickness of chimney or as to depth of flue.

In the modified form of this invention in Figures 5, 6 and 7 the deflector 47 is attached to the door 38 preferably by bolts 48 or the like. The deflector 47 is substantially L-shape, the inner end of which has its top wall curved downwardly. In this modified form the arcuate rod 36 of the preferred form is dispensed with, and the upper inner edge of the opening 15 in the chimney 10 is flared sufficiently to permit the door to close tightly with the forward end of the deflector 47 substantially horizontal and the rear end thereof inclined upwardly as shown in Figure 5. In other respects the two forms of the invention are similar. This modified form is particularly adapted for use in chimney structures which are not of very great thickness, such as are found in the ordinary dwelling house.

The door 38 is of sufficient weight to swing downward when the chain 46 is released, and to lift the deflectors 22, 25 and 26 against the top of the opening 15 and to the collapse expanding spring 39 until the inner edge of the flange 43 on the door 38 strikes the panel 18, thus effectively sealing the opening 15. The sections 22 and 25 of the air deflector may be adjusted one upon the other to position the hinged de-

flector plate 26 the desired distance within the flue 14, and the deflector plate 26 may be secured at the required angle for causing the draft of air as shown by the arrows 14^a to sweep downwardly at the necessary angle to sweep across the bottom of the flue 14.

It is of course understood that various changes and modifications may be made in the size proportion and kind of materials used in the construction of this invention without departing from the spirit thereof, the scope of the invention being restricted only by the breadth of the following claims:

15. What is claimed is:—

1. In a fuel economizer, a frame adapted to be mounted in the wall of a chimney, a door hinged to the frame for regulating draft through the frame, and a deflector connected to the door and projecting through the frame, said deflector being adjustable simultaneously with the door as the latter is opened and closed.

2. A fuel saving device comprising a frame adapted for insertion in a chimney wall and having a panel secured to its outer edges, a hinged door for closing the opening within the frame, a deflector having an open bottom within said frame and extending inwardly therefrom, operating means for said deflector to actuate it simultaneously with the opening and closing of said door.

3. A fuel saving device comprising a frame adapted to be mounted in the wall of a chimney having a panel on its outer edge a hinged door for closing the opening within the frame, a deflector within said frame, connecting means between the door and deflector for simultaneously opening and closing the same, a second deflector adjustably attached to the first deflector,

and a third deflector adjustably attached to said second deflector for movement therewith.

45

4. A fuel saving device comprising a frame adapted to be mounted in the wall of a chimney having a panel on its outer edge, a hinged door having inwardly extending flanges on its inner surface adapted to seat against said panel, a hinged deflector within said frame, a second deflector adjustably attached to said first deflector, a third deflector contained within said second deflector for deflecting downwardly the draft of air entering through said frame, and an adjustable connection between the deflectors and the door for simultaneously adjusting the same.

5. In a fuel economizer comprising a frame for installation in the wall of a chimney, a weighted door hinged at the front of the frame for normally closing the opening therethrough, a deflector pivoted to the top of the frame and projecting inwardly into the chimney, and a yieldable connection between the door and the deflector for adjusting the deflector by opening and closing the door.

6. In a fuel economizer comprising a frame for installation in the wall of a chimney, a door hinged upon the front of the frame for closing it, and a deflector connected to the inner side of the door and projecting into the chimney, said deflector being adjustable by the opening and closing of the door.

In testimony whereof, I have affixed my signature in presence of two witnesses.

ARTHUR H. STURGES.
